UNITED STATES PATENT OFFICE.

GEORGE J. CLINE, OF GOSHEN, INDIANA.

HARROW AND CULTIVATOR.

SPECIFICATION forming part of Letters Patent No. 245,133, dated August 2, 1881.

Application filed May 7, 1881. (Model.)

To all whom it may concern:

Be it known that I, GEORGE J. CLINE, a citizen of the United States, a resident of Goshen, in the county of Elkhart and State of Indiana, have invented a new and valuable Improvement in Harrows and Cultivators; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal section, and Fig. 2 is a plan view, showing in dotted lines the lateral adjustment of the bars.

This invention has relation to improvements in harrows; and it consists in the construction and novel arrangement of devices, as hereinafter set forth.

In the annexed drawings, the letter A indicates the harrow-frame, consisting of side bars, *a*, rear bar, *a'*, and cross-bar *a''*. This frame carries at its front end the tongue-supporting shaft or roller *a''*.

B represent the wheels.

The bars C, which support the teeth, are journaled to the side bars by means of suitable bearings.

The teeth D are spring-teeth, and they are pivoted by their middle portions to the bars or rock-shafts C, their lower or working ends, *d*, extending downward in curved form, and their upper ends, *d'*, extending to a transverse bar, E, to which they are pivoted. These bars E, therefore, connect the upper ends of the teeth of each series, and they are designed to be sufficiently long to extend over the side bars, *a*, so that their ends can be fastened thereto, pins *e* being used for this purpose, said pins passing through the holes in the bars E and in the side bars, *a*.

Other suitable fastenings easily applied may be used.

The bars E are designed to have handles *e'*, elongated loops being preferred, as shown in the drawings. This construction is designed to increase the elasticity of the teeth, the up-

ward extensions *d'* serving for this purpose without detracting from the strength of the curved working ends *d*. As the lower or working ends of the teeth are brought in action the upper ends thereof also bend in the reverse direction in taking the pressure as well as in the reaction.

The teeth being pivotally connected to both rock-shafts C and bars E, permit the latter to have an endwise or lateral adjustment, so that the teeth of successive shafts can be thrown into oblique positions alternately to the right and left. The bars E are fastened to the frame of the harrow by their ends, as above described, so that the oblique adjustment of the teeth can be secured so long as it may be desired to effect the complete harrowing.

From the rock-shafts C depend tongues *c'*, the lower ends of which are pivoted to a longitudinal bar, F, attached by a slot-and-pin connection to the lower end of a lever, G, pivoted to a cross-bar, and having its handle extending up within easy reach of the driver, and arranged to be held at any desired position by means of a notched catch, *g*. The construction described is designed to allow the rock-shafts to be readily adjusted to throw the teeth up or down, as may be desired. The frame is also adapted for use as a cultivator, the rock-shafts carrying the harrow-teeth being detached and shafts carrying cultivator-teeth substituted.

Having described this invention, what I claim, and desire to secure by Letters Patent, is—

The bars E, having their ends extending over the side bars of the frame, and adapted to be secured thereto, in combination with the rock-shafts C and the pivoted and adjustable teeth D, substantially as specified.

In testimony that I claim the above I have hereunto subscribed my name in the presence of two witnesses.

GEORGE J. CLINE.
